(57) **CLAIM**

The ornamental design for an ear cuff as shown and described.

DESCRIPTION

FIG. 1 is a front view of an ear cuff showing our new design; FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a cross-sectional end view thereof along the line 7-7 in FIG. 1;

FIG. 8 is a cross-sectional end view thereof along the line 8-8 in FIG. 1;

FIG. 9 is a cross-sectional end view thereof along the line 9-9 in FIG. 1;

FIG. 10 is a cross-sectional end view thereof along the line 10-10 in FIG. 1;

FIG. 11 is a cross-sectional end view thereof along the line 11-11 in FIG. 1;

FIG. 12 is a cross-sectional end view thereof along the line 12-12 in FIG. 1;

FIG. 13 is a cross-sectional end view thereof along the line 13-13 in FIG. 1;

FIG. 14 is a cross-sectional end view thereof along the line 14-14 in FIG. 1;

FIG. 15 is a cross-sectional end view thereof along the line 15-15 in FIG. 1;

(Continued)

FIG. 16 is a cross-sectional end view thereof along the line 16-16 in FIG. 1;
 FIG. 17 is a cross-sectional end view thereof along the line 17-17 in FIG. 1;
 FIG. 18 is a perspective reference view from a front side thereof; and,
 FIG. 19 is a perspective reference view from a rear side thereof.
